UNITED STATES PATENT OFFICE.

WILLIAM GRIKSCHET, OF DETROIT, MICHIGAN.

DRAIN-COCK.

1,267,763.

Specification of Letters Patent. Patented May 28, 1918.

Application filed March 14, 1918. Serial No. 222,278.

To all whom it may concern:

Be it known that I, WILLIAM GRIKSCHET, a citizen of the United States of America, residing at Detroit, in the county of Wayne 5 and State of Michigan, have invented certain new and useful Improvements in Drain-Cocks, of which the following is a specification, reference being had therein to the accompanying drawings.

10 The invention relates to drain-cocks particularly designed for use in connection with motor vehicle radiators and similar constructions, and it is the object of the invention to obtain a simple and inexpensive construction forming a normally tight closure and one which is easily opened when necessary.

In the drawings:

Figure 1 is an elevation of the drain-cock; and

20 Fig. 2 is a longitudinal section therethrough.

In the present state of the art it is usual to form drain-cocks of plug-valves, or in some cases to provide detachable screw-25 threaded plugs which must be removed when the radiator or other structure is to be drained. The plug-valves to form a tight closure must be carefully made and if not so made are apt to leak, while the screw 30 plugs are very inconvenient to manipulate. With my improved structure I combine the simplicity of a threaded plug-valve with a structure which will form a tight closure.

My improvement comprises a casing A 35 having a threaded nipple B for attachment to the radiator or other device and also preferably a polygonal portion C for engagement with the wrench. This casing is bored axially from its opposite ends so as to leave a

40 valve-seat D, and an angling bore E intersects the main bore at a point adjacent to said valve-seat. The main bore is threaded, as indicated at F, to engage a threaded stem G preferably formed with an integral T-

45 handle H. The threaded portion of the stem is of greater diameter than the shank portion and the threads terminate so as to leave the outer end of this portion of greater diameter uncut. The threads are also re-

50 moved from the outer portion of the main bore, as indicated at J, and from the inner end portion of the stem, as indicated at K. Thus the stem is free to be adjusted with clearance for the portion I in the portion J and also with clearance for the stem adja- 55 cent to the seat.

To retain the stem from accidental disengagement the outer end of the casing is formed with a fin, indicated by dotted lines at L, and after the stem is engaged with the bore this fin is spun in to form a shoulder 60 engaging the enlargement I. Thus the outer movement of the stem is limited by the striking of the portion I against the shoulder L, but in this position there is unobstructed 65 communication between the angling passage E and the main passage through the nipple B.

In the method of manufacture all of the operations for forming the casing can be 70 performed by a single chucking; also the threaded stem can be engaged with the casing while the latter is still chucked and the fin L spun down. This greatly simplifies the manufacture and reduces cost, while at 75 the same time the structure when complete has advantages over constructions heretofore used. Among these advantages are, first, that the valve when closed will be leak proof as the stem can always be forced to a true 80 seat; second, the valve can be easily opened at any time and without the use of tools; third, in case of clogging of the passage this may be cleared by the running of a wire or other instrument through the angling bore 85 and into the nipple; and fourth, the fact that the stem is provided with an enlarged portion which is free from threads and the casing with the spun fin effectually prevents the disengagement of the stem from the cas- 90 ing. This would not be the case if the threads were continued on the stem, as they would then cut through the fin by the application of a slight force.

What I claim as my invention is:

1. A drain-cock comprising a casing having an axial passage therethrough threaded in one portion thereof and provided with a contracted seat in another portion, said casing also having an angling passage intersecting the axial passage at a point adjacent to said seat, a stem for engaging said seat having a threaded portion for engaging the threaded passage in said casing, a shank of reduced diameter and an unthreaded portion 100 between said reduced shank and threaded portion, and a fin on said casing spun in to form a shoulder for engaging said unthreaded portion adjacent to said shank.

2. A drain-cock comprising a casing having an axial passage therethrough and an intersecting angular passage with a valve 110

- seat adjacent to the point of intersection, said axial passage being threaded, a stem for engaging said seat threaded to engage the threads of said axial passage having a shank of less diameter and an unthreaded portion of the diameter of the threaded portion and between the same and said shank, and a fin on said casing closed in to surround said shank and form a shoulder for engaging the larger diameter unthreaded portion, the latter being located to permit outward movement of the stem to clear the connection between said angular and axial passages.
- 15 3. A drain-cock comprising a casing having an axial passage and an intersecting angular passage therein with a valve-seat adjacent to the point of intersection, said casing having a threaded nipple at its inner end and a polygonal portion adjacent thereto and the outer end portion of said axial passage being threaded, a valve stem having a portion threaded to engage the threads of said axial passage having a shank of less diameter and an unthreaded portion of larger diameter than the shank portion between said shank and the threaded portion,
- 20 a portion of the threads in said axial passage being removed to permit movement of the unthreaded large diameter portion of said stem, and a fin on said casing turned in around said shank and forming a stop for engaging said unthreaded large diameter portion.
- 25 4. A drain-cock comprising a casing and a valve stem having a T-shaped head, said stem having a threaded portion, a shank portion of less diameter and an unthreaded portion of larger diameter than the shank portion between said shank and threaded portion and said casing being provided with an axial passage and an intersecting angling passage with a valve seat adjacent to the point of intersection, said axial passage having a threaded portion for engaging the threads of said stem, and an unthreaded portion at its outer end for receiving said unthreaded portion of larger diameter on said stem, and a fin at the outer end turned in around said shank and adapted to prevent the detachment of the stem from said casing.
- 30 40 45 50

In testimony whereof I affix my signature.
WILLIAM GRIKSCHET.
